UNITED STATES PATENT OFFICE.

THOMAS W. JENKS, OF AVALON, PENNSYLVANIA.

REINFORCING-BAR.

939,962.

Specification of Letters Patent. Patented Nov. 9, 1909.

Application filed February 2, 1907. Serial No. 355,416.

To all whom it may concern:

Be it known that I, THOMAS W. JENKS, of Avalon, Allegheny county, Pennsylvania, have invented a new and useful Improvement 5 in Reinforcing-Bars, of which the following is a full, clear, and exact description, reference being had to the accompanying drawings, forming part of this specification, in which—

10 Figure 1 is a perspective view of the bar; and Fig. 2 is a plan view partly in section.

My invention relates to the bars employed in reinforced concrete construction, and is designed to provide an improved form of 15 bar which will increase the strength of the structure and the bond between the concrete and bar.

To that end, it consists in a bar having continuous corner ribs and inclosed face recesses.

In the drawings, I show a preferred form of my improved bar, in which the bar 2 is provided on each face with a series of recesses or cavities 3, each of which is entirely 25 inclosed on all edges. I have shown the recesses in one face as staggered or alternated with those in the next adjacent face; and this is the preferred form. The complete inclosing of each cavity is secured by the 30 continuously extending edge ribs 4 at each corner and the somewhat closely adjacent transverse ribs extending at right angles to said ribs across the bar, alternately with the correspondingly disposed cavities 3. These 35 transverse ribs are, like the cavities, staggered or alternated throughout the length of the bar for each of the four sides, and a particular feature of advantage and novelty is that they merge into the surface of the corner ribs 4 flush therewith so that the surfaces of the bar at the junction of the transverse and longitudinal ribs are practically 40 continuous, irrespective of what form the middle portion of the transverse ribs may assume.

The device may be made in any suitable

manner, but preferably by the method of my prior Letters Patent 882,321 of March 17th, 1908.

The advantages of my invention result 50 from inclosing the cavities on all edges; thus providing a continuous corner rib, and merging the transverse ribs thereinto on the same plane, insuring symmetry, equal resistance to strains, and avoiding any sharp edges or 55 inconvenience in handling. This construction gives greater shearing strength. It also increases the tensile strength and the elastic limit of the bar. It also greatly increases the life of the rolls, and enables them to be 60 more easily made, and gives better distribution of the metal in rolling, since the excess metal flows into the raised portions in the sides between the recesses.

By the use of the continuous corner rib, 65 the recesses may be increased in length, thus decreasing the length of the raised portions, without decreasing the strength of the bar. I thus obtain a stronger bar without any 70 additional metal being needed.

The shape of the recesses may be varied, as well as the thickness of the inclosing walls, the depth of the recess, the cross-sectional shape of the bar, etc., without departing 75 from my invention.

I claim:—

A reinforcing bar for concrete construction substantially square in cross section, each face of the bar constituting a flat plane surface and being provided with depressions 80 included within the boundaries of such face, said depressions being shallow and bounded within inclined sides substantially square in configuration, the depressions in each face being staggered with relation to the depressions in each adjacent face.

In testimony whereof, I have hereunto set my hand.

THOMAS W. JENKS.
